US00D749591S

(12) **United States Design Patent**
Akana et al.

(10) **Patent No.:** US D749,591 S
(45) **Date of Patent:** ** Feb. 16, 2016

(54) **HOUSING FOR ELECTRONIC DEVICE**

(71) Applicant: **Apple Inc.**, Cupertino, CA (US)

(72) Inventors: **Jody Akana**, San Francisco, CA (US); **Bartley K. Andre**, Palo Alto, CA (US); **Shota Aoyagi**, San Francisco, CA (US); **Jeremy Bataillou**, San Francisco, CA (US); **Lucy E. Browning**, San Francisco, CA (US); **Miguel Christophy**, San Francisco, CA (US); **Daniel J. Coster**, San Francisco, CA (US); **Daniele De Iuliis**, San Francisco, CA (US); **Jonathan Corbin Denby**, Redwood City, CA (US); **Richard Hung Minh Dinh**, San Jose, CA (US); **M. Evans Hankey**, San Francisco, CA (US); **Julian Hoenig**, San Francisco, CA (US); **Richard P. Howarth**, San Francisco, CA (US); **Jonathan P. Ive**, San Francisco, CA (US); **Daniel W. Jarvis**, Sunnyvale, CA (US); **Duncan Robert Kerr**, San Francisco, CA (US); **Matthew Dean Rohrbach**, San Francisco, CA (US); **Peter Russell-Clarke**, San Francisco, CA (US); **Mikael Silvanto**, San Francisco, CA (US); **Jason Sloey**, Cedar Park, TX (US); **Ian Spraggs**, San Francisco, CA (US); **Christopher J. Stringer**, Woodside, CA (US); **Tang Yew Tan**, San Francisco, CA (US); **Eugene Antony Whang**, San Francisco, CA (US); **Rico Zörkendorfer**, San Francisco, CA (US)

(73) Assignee: **Apple Inc.**, Cupertino, CA (US)

(**) Term: **15 Years**

(21) Appl. No.: **29/527,929**

(22) Filed: **May 22, 2015**

(57) **CLAIM**

The ornamental design for a housing for electronic device, as shown and described.

DESCRIPTION

FIG. 1 is a bottom front perspective view of a housing for electronic device showing our new design; FIG. 2 is a front view thereof; FIG. 3 is a rear view thereof; FIG. 4 is a top view thereof; FIG. 5 is a bottom view thereof; FIG. 6 is a left view thereof; and, FIG. 7 is a right view thereof.

The broken lines in the Figures show portions of the housing for electronic device that form no part of the claimed design.

1 Claim, 5 Drawing Sheets
